METHOD FOR PRODUCING AND RECOVERING AROMATIC HYDROCARBONS

Charles H. Watkins, Western Springs, Ill., assignor to Universal Oil Products Company, Chicago, Ill., a corporation of Delaware

Application March 21, 1952, Serial No. 277,758

4 Claims. (Cl. 260—673)

This invention relates to an improved method for effecting a high production of aromatic hydrocarbons and recovering the latter. More specifically, the present improvement is directed to a combined operation which provides for commingling an aromatic rich hydrocarbon stream with a high temperature olefinic stream in a manner effecting the cracking of non-aromatic material in the aromatic rich stream and the conversion of at least a portion of the olefinic hydrocarbons to form additional aromatics in a substantially pure form permitting the fractional separation thereof.

In view of the present shortage of benzene and other aromatic hydrocarbons, it has been necessary to supply these critical materials from petroleum. However, one of the present problems in connection with the production and recovery of aromatics, such as benzene, toluene and the like from certain of the petroleum processing operations is that they can not be recovered by distillation to provide desired purities. For example, there are various desirable catalytic reforming operations which can be utilized to provide high yields of aromatic hydrocarbons, but the aromatics tend to form azeotropes with the resulting non-aromatic hydrocarbons and the separation of the aromatics in desired purities by distillation in order to provide industrial or nitration grade products is substantially impossible. Certain solvent extraction operations may be utilized to selectively separate the aromatics and provide the desired purities; however, the use of solvents may be expensive and troublesome, as well as require considerable contacting equipment in addition to fractionating apparatus.

It is, therefore, a principal object of the present invention to provide a desirable method for converting non-aromatic hydrocarbons in an aromatic rich stream so that there is a minimum of azeotrope formation, whereby fractional separation of the aromatics may be carried out satisfactorily.

It is also an object of the present invention to provide a method for commingling an aromatic rich stream with a high temperature cracked stream, particularly one high in ethylene and propylene, which can be converted to aromatics, while heating, cracking and substantially converting non-aromatic hydrocarbons into additional low molecular weight olefins, which in turn may be converted to provide still further quantities of aromatics.

A still further object of the invention is to effect the autothermic cracking of a low molecular weight paraffinic stream to provide a high temperature olefinic stream suitable for commingling with an aromatic rich stream and in turn effecting the conversion of the non-aromatic hydrocarbons of the latter into olefinic hydrocarbons which may provide the formation of additional aromatics.

In a broad aspect, the present invention provides a method for producing and recovering a high yield of aromatic hydrocarbons from an aromatic rich hydrocarbon stream in a manner which comprises, passing a cracked olefin containing hydrocarbon stream at a temperature in the range of from about 1400° F. to about 1600° F.

2

into contact with the aromatic rich stream and exothermically converting olefinic materials to form aromatic hydrocarbons while cracking non-aromatic components in the aromatic rich stream to form low molecular weight olefins and additional aromatic hydrocarbons, recovering a substantially aromatic hydrocarbon stream and subjecting it to fractional distillation to effect the production of desired substantially pure aromatic fractions.

The olefinic stream preferably comprises a high quantity of low molecular weight olefins such as ethylene and propylene which may react at high temperatures to form desired aromatic hydrocarbon fractions such as benzene, toluene, etc. The olefin containing stream may be supplied from any source, such as a portion of a thermally or catalytically cracked stream; however, in one desirable operation, low molecular weight paraffinic hydrocarbons, such as ethane, propane, or other normally gaseous hydrocarbons other than methane, as well as natural gas, all of which usually may be obtained economically, provide desirable paraffin hydrocarbons which in turn may be autothermically cracked to produce an olefinic stream.

Thus, in a more specific embodiment of the invention, suitable for producing and recovering a high yield of aromatic hydrocarbons, a normally gaseous paraffinic hydrocarbon is passed into admixture with a stream of controlled oxygen content and there is effected the oxidative cracking of said paraffinic stream to provide low molecular weight olefinic hydrocarbons, subsequently introducing an aromatic rich hydrocarbon stream into contact with said resulting olefinic oxidatively cracked stream and effecting the thermal conversion of a major portion of the non-aromatic hydrocarbons of said aromatic rich stream to provide additional low molecular weight hydrocarbons while simultaneously converting resulting olefins present to form additional aromatic hydrocarbons, withdrawing and subjecting a resulting substantially aromatic hydrocarbon stream to fractional distillation and recovering substantially pure aromatic fractions.

Preferably, the conversion of olefins to aromatic hydrocarbons is carried out in the temperature range of from about 1400° F. to about 1600° F. However, since the formation of aromatics from the low molecular weight olefins is an exothermic reaction, the resultant temperature may exceed 1600° F.; therefore, it is desirable to effect a controlled temperature within the aromatic forming zone. Preferably, this may be accomplished by introducing an aromatic rich stream into admixture with the resulting oxidatively cracked stream in incremental portions and at spaced points along the line of flow of the cracked stream as it passes through a suitable soaking chamber or through an aromatic conversion zone. In other words, by introducing aromatic rich stream at a temperature which is something less than 1600° F. in stepwise increments, the temperature may be controlled in the conversion zone to prevent it from becoming excessive. In view of the fact that the aromatic formation from olefin requires relatively long periods of contacting, it is desirable to provide an elongated soaking chamber for passing the admixture of the olefin stream and the aromatic rich stream. Alternatively, it may be desirable to provide a series of two or more soaking chambers, or aromatic formation chambers, through which the mixed stream may pass, and into which the aromatic rich stream may be introduced by increments.

Where it is desired to obtain high yields of aromatics, it is necessary that the contact or residence time in the conversion zone or zones be sufficient to appreciably reduce the olefin content of the autothermically cracked stream. Also, it is preferable that the ethylene content in the stream leaving the aromatization zone should be less than about 12 weight percent of the total C₂+ hydro-

carbons that are charged to the zone. If the charge to the aromatization zone comprises an olefin other than ethylene, substantially all of the olefin undergoes conversion to ethylene, aromatics, and paraffins. Hence, ethylene is the only olefin that appears in the aromatization zone effluent in significant concentrations, and for this reason ethylene concentration may be utilized as an operating control, regardless of the particular olefin or olefins charged to the aromatization zone.

As previously noted, it is desirable to provide the cracked olefin containing stream by the oxidative or auto-thermic cracking of hydrocarbon heavier than ethylene. For example, ethane or any non-aromatic hydrocarbon containing at least 2 carbon atoms per molecule may be preheated and intimately mixed with a preheated air or oxygen containing stream having greater than about 20% oxygen by volume and allowing the same to react. The amount of oxygen relative to the amount of hydrocarbon is preferably in an amount sufficient to bring about the conversion of at least 90% of the paraffinic charge stream, since it has been found that conversions of at least about 90% to low molecular weight olefins is essential to prepare an olefinic hydrocarbon stream which will in turn provide a desired exothermicity upon subsequent admixture with the aromatic rich stream in the aromatization zone.

The pressure for effecting the cracking of nonaromatic hydrocarbons and the formation of additional aromatics by contacting a high temperature olefin containing stream with the aromatic rich stream may be in the range of from about 0 to 400 p. s. i. g. At pressures above 400 p. s. i. g., there may be considerable effect from undesirable side reactions. At pressures below about 75 p. s. i. g., there is little trouble with carbon formation, or methane formation, while above 100 p. s. i. g., there may be an increase in the formation of these undesired products, and further, it is generally desirable to operate in the range of from 0 to 50 p. s. i. g. In any case, from the standpoint of obtaining maximum yield and reducing side reactions, it is preferable to operate below about 400 p. s. i. g. However, since the space velocity in the aromatic formation zone may be increased with increasing pressures, and the resulting size of an aromatizing or soaking chamber, or chambers, may be proportionately decreased with increased pressures, it may in some instances be desirable to utilize higher pressures, say within the range of from 100 to 400 p. s. i. g.

Reference to the accompanying drawing and the following description thereof will aid in clarifying the operation of one embodiment of the invention, and point out additional advantageous features in connection therewith.

Ethane or a stream of low molecular weight paraffinic hydrocarbons is passed by way of line 1 and valve 2 through a suitable heater 3 and subsequently through line 4 to a mixing zone 5, while at the same time air or other oxygen containing stream is introduced by way of line 6, valve 7, to a heater 8 and then passed from the latter through line 9 into mixer 5. Each of these streams are preferably heated or preheated to a relatively high temperature say of the order of 1000° F. or more, so that they will spontaneously interact by partial combustion in the mixing zone 5. The mixer 5 is internally designed to provide rapid intimate mixing of the two streams and the discharge thereof directly into a reaction zone 10, whereby there is oxidative cracking of a portion of the hydrocarbon charge stream. In the mixing and reaction zones, there is partial combustion of a portion of the hydrocarbon stream to yield carbon oxides, hydrogen and some water, while the resulting high temperature products effect the thermal cracking and decomposition of a substantial portion of the remaining hydrocarbon stream to provide principally ethylene and minor amounts of other gases.

The reaction zone 10 is preferably insulated and internally lined to provide a substantially adiabatic reaction zone. This reaction zone may also have baffles or a

suitable packing material, such as Raschig rings, so that there is continued intermixing of the combustion gases and the hydrocarbon stream and resulting decomposition products. As hereinbefore noted, it is preferable to effect the oxidative cracking in a manner providing combustion reactions and cracking reactions that effect a 90% conversion of the ethane and heavier hydrocarbons in the charge stream.

Normally, the preheating of the charge streams and the quantity of oxygen with respect to the quantity of ethane or other hydrocarbon is such as to provide a maximum cracking temperature in the range of from about 1600° F. to about 2000° F.

The resulting olefinic hydrocarbon stream from the reactor 10 is passed directly from reactor chamber 10 into an elongated cracking and aromatizing chamber 11 at a resulting conversion temperature and without substantial loss of heat. Chamber 11 in effect provides a soaking chamber for the formation of aromatics as well as a cracking chamber for the conversion of non-aromatic hydrocarbons which are introduced thereto. In the present embodiment, the aromatic rich stream which is to undergo further conversion and aromatization in accordance with the present invention, is passed by way of line 12, valve 13 and heater 14 into a distributing line 15. From the latter, divided portions of the aromatic stream may be introduced stagewise into the cracking and soaking chamber 11. The heater 14 is utilized to preheat and raise the temperature of the aromatic rich stream to an economically desirable level, say of the order of from about 1100° F. to about 1200° F. In any case, the temperature of this stream will be less than about 1600° F. so as to prevent the conversion temperature within chamber 11 from becoming excessively high as the exothermic reaction proceeds. A portion of the aromatic rich stream passes from distributing line 15 through line 16 and valve 17 into a first portion of the cracking and aromatizing chamber 11 and therein becomes admixed with the oxidatively cracked olefinic stream from reactor 10 so that there is a resulting cracking of non-aromatic hydrocarbons in the introduced stream and the conversion of olefins into benzene and other aromatics. It is also to be noted that the non-aromatic hydrocarbon components of the aromatic rich stream, which are introduced by way of lines 15 and 16 will be converted to ethylene and other low molecular weight olefinic hydrocarbons so that they are thusly present to provide for the further production of aromatic hydrocarbons.

Since the aromatic formation reaction is exothermic, the temperature within the contacting chamber 11 tends to increase above the desired level, say of the order of 1600° F., and it is therefore desirable to control and maintain this temperature below that level. In the present embodiment, a second portion of the aromatic rich charge stream passes by way of a line 18 and valve 19 from header line 15, and the resulting mixture within the chamber is thus partially quenched and maintained below an excessively high temperature level. Similarly, a third portion of the aromatic rich stream passes by way of line 20 and valve 21 into the chamber 11 at a successive point along the line of flow of the olefinic hydrocarbon stream. Thus, by the introduction of incremental portions of the aromatic rich stream into contact with the resulting olefinic hydrocarbon stream at spaced points along its line of flow, the exothermic reaction temperature may be successively reduced and maintained within the desired conversion range.

The chamber 11 is also preferably internally refractory lined, in a manner similar to that of chamber 10 so that there is an iron free surface and so that there is a minimum of heat loss from the conversion zone with optimum conversions to the desired aromatic fractions. While the present embodiment indicates a single long aromatization chamber 11, it is to be noted, that two or more substantially separate or individually lined conver-

sion chambers may be placed in series in lieu of the single chamber. In which case, the aromatic rich stream would be introduced by increments into admixture with the resulting olefinic stream at the inlet of each of the conversion chambers.

The resulting substantially aromatic stream being withdrawn from the end of chamber 11 passes by way of line 22 and valve 23 to a suitable quenching and separating chamber 24. It is desirable in this zone to effect the separation of heavy asphaltic-like aromatic oils from the product stream prior to passing it through the various fractionating zones. Thus, in the present embodiment, a relatively heavy quenching oil such as naphthalene, or a material heavier than xylene may be introduced through line 25 into the upper portion of the quenching and separating chamber 24 to effect the cooling of the product stream and to permit the recovery of the undesired heavy asphalt-like oils from the lower portion of the column 24. These oils are withdrawn by way of line 26 and valve 27, while the lower boiling cut containing naphthalene and lighter aromatic materials is discharged overhead through line 28 and valve 29. Preferably, the cooling effected in the separating chamber 24 is such that the materials being withdrawn are at a temperature say of the order of about 600-700° F. It is to be noted, that a temperature of 500° F. or lower may permit condensation of some of the naphthalene or more valuable aromatics. Thus, the lower boiling and more valuable aromatic products are introduced into the lower portion of an absorber column 30 by way of line 28 and valve 29. Subsequently, the aromatic fractions in column 30 are contacted by a suitable absorption oil, which may for example be a 200-400° F. aromatic cut, containing toluene and heavier aromatics. This cut is introduced by way of line 31 and a suitable distributing header 32. A gaseous stream, high in olefin content, is discharged from the upper end of the absorber column 30 by way of line 33 and valve 34 while from the lower end of the column, the desired aromatics are withdrawn by way of line 35 and valve 36 for subsequent introduction into a benzene separating column 37. As diagrammatically indicated, the benzene column 37 effects the overhead discharge of a substantially pure benzene aromatic fraction by way of line 38 and valve 39, while a stream containing toluene, xylene, and heavier aromatics is discharged by way of line 40 and valve 41. A portion of this heavier cut, as indicated, may be withdrawn from line 40 by way of line 31 and control valve 42. Thus, a regulated quantity of absorbing oil may be passed to column 30. Still another line 43 having valve 44 is indicated diagrammatically as connecting with line 31, and is suitable to permit the introduction of a different absorbing oil into column 30, where such oil is to be supplied from a source other than from the bottoms of benzene column 37.

The bottoms stream from column 37 is introduced into a toluene fractionation column 45, from which an overhead toluene fraction is discharged by way of line 46 and valve 47. While from the lower end of column 45, by way of line 48 and valve 49, there is discharged the aromatic bottoms stream containing xylene, naphthalene and heavier desired materials. The aromatics from line 48 are subsequently introduced into a xylene fractionating column 50, from which is discharged an overhead xylene fraction by way of line 51 and valve 52. The heavier aromatic oils from column 50 are discharged by way of line 53 and valve 54 and may, if desired, undergo further separation and fractionation to recover naphthalene, etc. The present embodiment also indicates a portion of the heavier aromatic oils from the bottom of the xylene column 50 as passing by way of line 53 and line 25, having valve 55, to provide the quenching oil that is introduced into the upper portion of the quenching and separating chamber 24.

Since, in accordance with the present invention, the

non-aromatic hydrocarbons contained in the aromatic rich stream are substantially eliminated within the conversion chamber 11, it is to be noted that there is but little formation of azeotropes between the non-aromatic hydrocarbons and the aromatic hydrocarbons, and that the separation effected in the various fractionating columns 37, 45 and 50 may be carried out to effect the recovery of substantially pure aromatic fractions, which may normally meet industrial or nitration-grade requirements.

It is also to be noted that the present embodiment does not limit the origin of the aromatic rich charge stream which undergoes further conversion to aromatics by contact with the oxidatively cracked olefinic stream. In other words, the aromatic rich stream may be the product stream from a thermal or catalytic reforming unit, a dehydrogenation unit and the like, or other source providing a hydrocarbon stream with a high degree of aromatic components. It may, for example, be advantageous to pre-fractionate a natural gasoline stream to separate C₄ and lighter normally paraffinic hydrocarbons as an overhead stream and charge them to the mixer 5 of the autothermic or oxidative cracking section of the present embodiment, while the C₅ and heavier components of the fractionated natural gasoline stream may be passed to a catalytic reforming zone and therein contact suitable aromatizing catalysts so that there is a resulting reformed gasoline stream producing an aromatic rich stream. This latter stream may then be introduced, by way of line 12, into the cracking and aromatizing zone 11 for further conversion of the non-aromatic hydrocarbons in accordance with the embodiment of the present invention.

I claim as my invention:

1. A method for producing and recovering a high yield of aromatic hydrocarbons, which comprises, passing a normally gaseous paraffinic hydrocarbon stream into admixture with a stream of controlled oxygen content and effecting the oxidative cracking of said gaseous hydrocarbon stream to provide a low molecular weight olefinic hydrocarbons at a temperature in the range of from about 1400° F. to about 1600° F., passing the resulting olefinic hydrocarbon stream at the aforesaid resulting temperature into a confined cracking and aromatization zone at a pressure below about 400 p. s. i. g. and commingling with said product stream an aromatic rich hydrocarbon stream, the latter stream being introduced into said conversion zone and into admixture with said oxidatively cracked stream in incremental portions along the line of flow of the latter in said zone, and with said aromatic rich stream being introduced into said conversion zone at a temperature of less than 1600° F. and thereby controlling exothermic aromatics forming reactions to effect the thermal conversion of a major portion of the non-aromatic components of said aromatic rich stream into additional olefins and aromatic hydrocarbons while simultaneously converting resulting olefinic components from said oxidatively cracked stream into additional aromatic hydrocarbons, withdrawing a resulting substantially aromatic hydrocarbon stream from said zone and subjecting it to cooling and fractional distillation and recovering desired substantially pure aromatic fractions.
2. A method for producing and recovering a high yield of aromatic hydrocarbons, which comprises, passing a normally gaseous paraffinic stream into admixture with a stream of controlled oxygen content and effecting the oxidative cracking of said hydrocarbon stream providing a low molecular weight olefinic hydrocarbon stream at a temperature within the range of from about 1400° F. to about 1600° F., passing the resulting olefinic hydrocarbon stream at the aforesaid resulting temperature into a confined cracking and aromatizing zone at a pressure of less than about 400 p. s. i. g. and commingling with said olefinic stream an aromatic rich hydrocarbon stream, introducing the latter stream into said cracking and aroma-

tizing zone in incremental portions along the line of flow of the oxidatively cracked olefinic stream, effecting the mixture of the incremental portion of said aromatic rich hydrocarbon stream with said olefinic stream in a manner providing the thermal conversion of a major portion of the non-aromatic components of said aromatic rich stream into additional olefinic and aromatic hydrocarbons while simultaneously converting resulting olefinic components from said oxidatively cracked stream into additional aromatic hydrocarbons, with said portions of said aromatic rich stream being introduced into said zone at a temperature of less than 1600° F. and thereby controlling the resulting exothermic reaction effecting the conversion of olefinic hydrocarbons to aromatic hydrocarbons, withdrawing a resulting substantially aromatic hydrocarbon stream from said zone and quenching it with a relatively heavy aromatic oil stream to effect the cooling and separation of resulting substantially heavy non-volatile aromatic oils, passing a resulting quenched and separated aromatic hydrocarbon stream to a fractionation zone and effecting the fractional distillation and recovery of desired substantially pure aromatic fractions.

3. The method of claim 2 further characterized in that said separated and quenched aromatic stream is subjected to countercurrent contact with an aromatic absorption oil prior to passing the stream to said fractionation zone, and said absorption oil comprises an aromatic oil boiling in the range of from about 200-400° F.

4. The method of claim 2 further characterized in that said heavy aromatic quenching oil contacting said resulting aromatic product stream comprises a substantially heavy aromatic oil boiling in the range of from about 600° F. to about 800° F.
